US00D933044S

(12) **United States Design Patent** (10) **Patent No.:** **US D933,044 S**
(45) **Date of Patent:** **** Oct. 12, 2021**

(54) **SPEAKER**

- (71) Applicant: **Alco Electronics Limited**, Sha Tin (HK)
- (72) Inventors: **Wilson Wai Sing Leung**, Sha Tin (HK); **Wai Lun Wong**, Sha Tin (HK)
- (73) Assignee: **Aleo Electronics Limited**, Sha Tin (HK)

(**) Term: **15 Years**

(21) Appl. No.: **29/715,728**

(22) Filed: **Dec. 4, 2019**

(30) **Foreign Application Priority Data**

Jun. 6, 2019 (HK) 1913910.6M002

(57) **CLAIM**

The ornamental design for a speaker, as shown and described.

DESCRIPTION

FIG. 1 is a front perspective view of a speaker of the present invention;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof; and,

FIG. 8 is a right side view thereof.

The broken lines shown in FIG. 6 illustrate portions of the speaker that form no part of the claimed design.

1 Claim, 7 Drawing Sheets
